UNITED STATES PATENT OFFICE.

JOHN O. MCKEAN, OF WESTFIELD, MASSACHUSETTS, ASSIGNOR TO FOSTER MACHINE COMPANY, OF WESTFIELD, MASSACHUSETTS, A CORPORATION OF MASSACHUSETTS.

SUPPORT FOR BOBBINS OR COPS.

1,229,491.

Specification of Letters Patent.

Patented June 12, 1917.

Application filed May 1, 1916. Serial No. 94,535.

To all whom it may concern:

Be it known that I, JOHN O. MCKEAN, a citizen of the United States, residing at Westfield, in the county of Hampden and

5 State of Massachusetts, have invented new and useful Improvements in Supports for Bobbins or Cops, of which the following is a specification.

My invention is a support for bobbins or 10 cops during the process of unwinding the same, so designed and arranged as to maintain frictional braking engagement with the bobbin throughout the unwinding process.

In the drawings:

15 Figure 1 shows the standard for the support;

Fig. 2 is a plan view of Fig. 1;

Fig. 3 shows the movable element of the 20 device;

Fig. 4 is a view of the support at right angles to the view in Fig. 3; and

Fig. 5 shows the complete assembly, in perspective, on an enlarged scale.

In the preparation of yarns and the like 25 for use in the making of textiles, it is necessary to unwind the yarn from bobbins, spools, cops and the like and to re-wind it onto some other container. My invention is a support or holder for the bobbin that is to 30 be re-wound, during the re-winding operation. The re-winding is accomplished by attaching the free end of the yarn upon the bobbin to be unwound to the cop, spool or bobbin upon which it is to be re-wound. The 35 re-wind bobbin is then rotated and the yarn drawn off the original bobbin. This is accomplished at high speed, the yarn leading upward to the drawing bobbin or cop, and, due to this draft upon the thread the delivering 40 cop or spool is under some lifting strain, which tends to raise it, and, as in practice neither the draft nor the resistance is uniform, the result is that the delivering cop is continually lifted and dropped under 45 these changes of actuating force, continually varying or destroying the tension to the detriment of good spooling.

My device consists essentially of a spring 50 supported seat, to receive and sustain the delivering cop and a guide spindle, upon which the cop may be mounted, and which operates to keep the cop always in line with the support. Any lifting effect upon the cop, whether caused by increased draft or increased 55 resistance, is neutralized as to any

evil effects, since the spring supported cradle upon which the surface of the delivering cop rests, instantly follows the slightest rise and maintains at all times frictional engagement with the cop, gradually releasing the friction as the cop lifts and the gravity of the cop is more or less overcome and gradually re-instating normal braking action when the cop falls as the draft is reduced.

In the drawings the standard, a , for the support, b , is shown mounted upon a base plate, a' , which may be secured either to the floor or to some part of the spooling machine as desired. I have shown it as arranged to be bolted to the floor by bolts, a^2 .

Rising 60 also from the base plate is an upright member, a^3 , having a projection at its upper end which is slotted, as at a^4 , for a purpose to be later indicated. The support, b , is preferably of curved contour on its upper surface 65 (see Fig. 4) to afford a good seat and braking surface to a cop of any size. The support, b , carries upon its underside a hollow member, b' , having a bore calculated to receive the standard, a , in telescoping fashion. 70

(See Fig. 3, in which the bore of b' is indicated by dotted lines.) Between the base plate, a' , and the support, b , and surrounding the standard, a , and the member, b' , is 75 interposed a helical spring, H , upon the upper end of which the support, b , is supported. Depending also from the underside of b is a short guide rod b^2 of a size suitable to enter the slot a^4 in the upper end of a^3 , to prevent the support b from turning on its 80 axis and to guide it in its rise and fall. Co-

operating with this guided support, b , is a guided spindle, s , mounted at one end of a pivoted lever, s' , which is, in turn, pivoted 85 upon the upper end of a standard, s^2 , suitably supported on the floor or secured to some part of the spooling machine. The 90

pivoted lever s' is so mounted that its upper surface is above the top of the standard, s^2 , so that a balance weight, W , may be freely 95 moved along the lever, s' , from one end to the other, thus enabling the operator to control the weight pressing upon the support, either counterbalancing it in part by moving the weight to the side of the pivot opposite 100

that upon which the cop is, or increasing the weight by adjusting the weight on the same side of the pivot with the cop.

The operation will be obvious from the above. The parts are assembled as clearly 105

shown in the drawings. The bobbin or the like to be unwound is placed upon the spindle, *s*, where it rotates freely, actuated by the draft of the thread or yarn as it is drawn off. 5 The under surface of the cop rests upon the support, *b*, and the weight of the cop, plus or minus what may be added or counter-weighted by the weight, *W*, as it may be adjusted, compresses the spring *H*. When the draft is sufficient to disturb the balance of things the cop and the support, *b*, rise slightly, the support always in contact with the surface of the cop, the cop being guided and maintained in proper relation to the support by the swinging spindle *s* upon which it is mounted. 10 15

I claim:

1. In a supporter for spools or the like, the combination of a spool-sustaining support; a

spring sustaining said support and means 20 engaging the spool to guide the spool in movements in a direction to and from the support and retain it in proper relation to the support while the spool is unwound.

2. In a supporter for spools or the like, 25 the combination of a support; a spool receiving spindle, mounted upon one end of a pivoted beam; that beam and a weight adjustable upon either side of the beam pivot to increase or decrease the pressure of the 30 spool upon the support.

Signed by me at Westfield, Mass., this 27th day of April, 1916.

JOHN O. McKEAN.
